UNITED STATES PATENT OFFICE.

ABRAHAM G. SHIDEED, OF LAWRENCE, MASSACHUSETTS.

DEVICE FOR HANDLING BROKEN ENDS.

1,075,161.

Specification of Letters Patent.

Patented Oct. 7, 1913.

Application filed May 28, 1910. Serial No. 563,932.

To all whom it may concern:

Be it known that I, ABRAHAM G. SHIDEED, a citizen of the Empire of Turkey, residing at Lawrence, in the county of Essex and State of Massachusetts, have invented certain new and useful Improvements in Devices for Handling Broken Ends, of which the following is a specification.

10 My invention relates to devices for taking care of the broken ends of roving, sliver or yarn in the various processes of textile manufacture. It can be used alone or with different attachments and on various machines wherein such roving, sliver or yarn passes through delivery rolls.

In the accompanying drawings, I show different embodiments of my invention and its application to various machines.

20 In the drawings, Figure 1 shows in perspective, my device attached to a drawing box such as is used in worsted spinning with portions of the rolls, pulleys, spindles and fliers broken away to show the construction

25 Fig. 2 is a sectional side view of such a drawing box with my device attached. Fig. 3 is a top view of the block by which my device is attached to the spindle bracket either alone or in connection with another stop

30 motion. Fig. 4 is a front view of a drawing box showing my present device applied to the delivery rolls of a drawing box in connection with a stop motion for which I received Patent No. 885,875 dated April 28,

35 Fig. 5 shows my invention applied to the ordinary drawing frame used in cotton spinning. Fig. 6 shows it applied to the delivery end of a cotton card. Fig. 7 shows it applied to a slubbing machine. Fig. 8

40 shows it applied to a cap spinning frame.

Referring to the first four figures which show my device applied to a drawing box, I will describe the construction. The purpose of a drawing box is to twist the ends

45 A of the sliver as they are delivered from the drawing rolls G and H to form the roving K and to wind the roving upon the bobbins B. The spindles C, C are actuated by pulleys E, E. Each spindle C carries a flier

50 F provided with eyes 10 and 11 and each is in the form of a tube at its upper end through the sides of which is an opening 12. The bobbins B, B are loosely mounted upon the spindles C, C, and rest upon friction washers L, which rest upon plates M fastened to lifter plate N. They could re-

volve freely upon spindles C, C were it not for the friction of washers L. Each sliver end A is delivered by the rolls G and H and passes through the top of the spindle 60 C out through the opening 12 and through one of the eyes 10. From thence it is wound around the arm of the flier F and passes through the eye 11 onto the bobbin B. The bobbin B is rotated by the drag of the roving K coming from the arm of flier F, but at a slower speed than the flier on account of the drag of washer L, with the result that a twist is imparted to the roving and it is also wound upon bobbin B. It is distributed evenly upon bobbin B by the rise and fall of lifter plate N. This is the "washer drag" system. The bottom of each spindle C rests in a suitable opening in a pulley E, each of which is actuated 70 through belts and pulleys of well known construction by fast pulley O on shaft 40.

In the well known type of machine to which this device is applicable, the spindle is supported at the top by a spindle bracket 80 30 into which sets the bearing cup 50 which can be passed over the top of the spindle C and pushed into the opening in the bracket and dropped into place therein, thus detachably holding the spindle in place. 85 Each spindle bracket 30 is attached to the fixed rail R of the usual construction. The lower delivery rolls H are usually fluted and are fixed to the driving shaft 20. The upper delivery rolls G are pressed by springs 90 against rolls H and are usually covered with leather or smooth cloth. These rolls G are driven by frictional contact with rolls H. Rolls H are usually of steel on their surfaces. In the case of a break in the roving between the contact point of rolls G and H and the bobbin B, the drag upon the roving ceases and no more is drawn into the top of spindle C. Either one of two things must happen. Either the roving which is 95 still being delivered falls over the spindle bracket 30 and winds up upon the top of the still revolving spindle C, in which case it will be taken care of by my Patent No. 885,875 referred to by stopping the machine, 100 or if it does not fall over the spindle bracket, it will be picked up by the upper leather covered roll G to which it will adhere in preference to the steel covered roll H. The result is that it continues to wind 105 until noticed by the attendant. Thereby great waste is caused.

55

110

My device comprises a spool 60 which preferably has at both ends a head 61 and is carried loosely by a spindle 62. Spool 60 is preferably covered with rough cloth, felt, wire or other material 90, to which roving will cling in preference to the leather 91 of roll G. This spool 60 is also relatively much smaller in diameter than roll G. In fact it should be made as small as possible. Spindle 62 is carried by a rocker arm 64 pivoted at 92 to a block 65 and bent at one end to avoid driving roll H and driving shaft 20, so that it can come up proximate and a little to one side of roll G. It has a slot 66 at this end in which the end of spindle 62 is adapted to slide. Spindle 62 is also threaded at the end to receive an adjusting nut 150 by which it may be adjusted along slot 66. The other end of rocker arm 64 is pivoted to a link 93 which is also pivoted to a connecting arm 94 fixed to a pivot shaft 70. For each set of drawing rolls G and H, I provide the above arrangement of spool 60, rocker arm 64, link 93 and connecting arm 94.

The pivot shaft 70 is carried by bearings which may be attached to any convenient part of the frame 71, 71 of the machine. The arms 94 one for each set of drawing rolls, are fixed to this pivot shaft as stated. A trigger arm 73 is also carried at a suitable point by pivot shaft 70. To counterbalance the weight of spool 60 and arm 73, I provide a counterweight arm 74 upon which is the counterweight 75 detachably attached thereto by means of a set screw.

In this type of machine, the belt is thrown from the fast pulley O to the loose pulley P by a shipper connection operated by a handle 80 carried by a shipper shaft 81. I fix a shipper arm 82 to the shipper shaft 81 and pivot to the shipper arm 82, a shipper rod 83 which is supported by and slides in bearings 84 and 85 fixed to any convenient part of the machine. A collar 86 of greater length than the throw of the shipper rod 83 is adjustably attached thereto by means of a set screw. Around the shipper rod 83 resting at one end against the bearing 84 and at the other end against collar 86 is a spiral spring 87. When the belt is brought on the fast pulley O by handle 80 to start the machine, the spiral spring 87 is compressed and collar 86 is brought into such position that trigger arm 73 will be brought up by the counterweight 75 in front of collar 86 thus retaining it in that position. It will be seen that if trigger arm 73 is depressed out of the way of collar 86, spiral spring 87 will expand carrying with it the collar 86, shipper rod 83 and shipper arm 82 and will throw the belt from the fast pulley O onto the loose pulley P thus stopping the machine. If a break occurs in the roving A at any point after it leaves the con-

tact point between the delivery rolls G and H, the loose end will ordinarily fall over the spindle bracket or else cling to leather covered roll G and be carried around thereby, and wound thereon as described. This causes a great waste of the roving.

With my device, the operation is as follows: Spool 60 is maintained by weight 75 acting on rocking arm 64 in contact with delivery roll G, at all times and is rotated by frictional contact therewith at all times while roll G is rotated by roll H. With my device, when a break occurs as illustrated in Fig. 2, if the loose end is picked up by roll G it is carried along as shown by the dotted lines until it strikes the point of contact with my spool 60. As spool 60 is covered with felt or other tenacious material 90, the end is picked from roll G and winds upon spool 60. As I make the diameter of spool 60 relatively very much less than the diameter of roll G and as it is rotated by frictional contact with that roll, the roving rapidly winds up and forms a bunch as shown in Fig. 1. This bunch forces spool 60 outward to the position shown by the dotted lines in Fig. 2. This outward movement rocks rocker arm 64 thereby lifting link 93 which through connecting arm 94 rotates shaft 70 sufficiently so that trigger arm 73 is moved downward clear of collar 86. This releases spring 87 which actuates the shipper and stops the machine as described. When the machine is stopped, the broken roving is readily pieced. The roving on spool 60 may be unwound to the end, which can be united to the other broken end thereby avoiding any waste whatever, or it may be broken, pieced and then the remnant removed from the spool, thereby saving time.

In Fig. 5 is shown the application of my rough skin spools to a drawing frame of a type common in cotton yarn manufacture. The roving 101 passes between the drawing rolls 102 and 103 which are shown as located in three sets close together. It is immaterial with what these rolls are covered provided it does not cling too tenaciously to the roving 101. In this case, I use rough skin spools 104 and 105 carried loosely by spindles on arms 106 and 107 which are pivoted respectively 108 and 109. They are so located that the top spools 104 rest on the top of rolls 102 and the bottom spools 105 are held in contact with the bottom rolls 103 by the pressure of a weight 110 acting on arm 107. The pivot rod 70, trigger arm 73, shipper rod 83 and collar 86 are of the same or similar construction to those used in the drawing box above described. Arm 106 has an ear 111 and arm 107 has an ear 112 which engage respectively the noses 113 and 114 fixed to pivot shaft 70. It can be readily seen that if the roving breaks between the

rolls or between the rolls and the head 115, it will be picked up by some one of the drawing rolls 102 or 103 as shown by the dotted lines and carried as far as one of my 5 spools. When it reaches a spool, it will wind thereon and force it outward carrying its supporting arm 106 or 107. This action operating through the ear 111 and nose 113 or ear 112 and nose 114 will force downward 10 trigger arm 73 thus releasing collar 86 and operating the shipping rod 83 to stop the machine. In the same way, my device may be applied to the delivery end of a carding machine as shown in Fig. 6. 120 is the 15 sliver, 121 the can, 122 the upper delivery roll and 123 the lower delivery roll. In this construction, my spool 124 is carried by a pivot arm 125 which connects a suitable link 126 with an arm 94 carried by pivot shaft 20 70. The collar 86, shipper rod 83 and trigger arm 73 are of the same construction as above described. The link 126 may carry a weight 127 to overbalance spool 124 and trigger arm 73. In this construction, if the 25 sliver breaks, it is almost certain to fall downward by gravity as shown in the dotted lines over the lower delivery roll 123 from which it is picked up by spool 124.

In Fig. 7 I show my device applied to a 30 slubber, roving machine, dandy, reducer, or speeder. The roving 130 is delivered by driving roll 131 and leather covered roll 132 to the flier 133. The spool 60 and arm 64 are of substantially the same construction 35 as shown in the drawing box shown in Figs. 1 to 4 and are connected to the shipper rod in the same way.

My rough skinned spool can also be used to advantage in connection with a machine 40 like a cap spinning frame such as shown in Fig. 8 or in fact in connection with any spinning frame or other machine where it is not desired to stop the whole machine when a single end breaks. In the construction 45 shown in Fig. 8, the lower delivery rolls 140 are the driving rolls while each pair of the upper rolls 141 are pressed downward by a spring 142 which bears on their shaft 143 between them. If an end 144 breaks and 50 winds on one of these delivery rolls, it raises that end of their shaft which causes extra pressure on the other roll and therefore uneven work. In such machines, it is not desirable to stop the whole machine when a 55 single end breaks as there are so many ends that such stopping would cause needless loss of production. It is therefore the custom to allow the end to wind on one of the delivery

rolls from which it is afterward stripped and the end broken between the fingers of 60 the operative who then pieces the broken ends. In using my rough skinned spools in such a machine, I prefer to rest the upper spool 146 in guides 145 as shown, whereby it is kept in contact with the upper delivery 65 roll 141 by gravity. The lower spool 147 is supported on each end by a carrier 148 so shaped that it has a rear arm and a forwardly projecting sloping arm of such shape that the lower spool can be pulled out 70 readily and replaced readily. These carriers are carried by suitable pivoted members 149 and are held upward by a suitable weight 150 as shown.

In the construction shown in Fig. 8, after 75 an end breaks, it is picked up by one of the spools 146 or 147 where it winds up without disturbing the equilibrium of the paired delivery rolls or otherwise causing trouble. When the operative is ready to strip, he 80 breaks the end and strips in the usual manner afterward removing the spools, and removing the waste end therefrom either by 85 unwinding or otherwise stripping it. As the delivery rolls 140 and 141 are always kept clear by the rough skinned spools, it is never necessary for the operative to clear 90 them and he can piece the broken ends first and then unwind or otherwise strip the spool.

My invention can be used upon almost 95 every machine in the drawing room and on some in the combing room. In fact it can be used upon any machine which delivers sliver or roving.

What I claim as my invention and desire to cover by Letters Patent is:—

In a stop motion for drawing boxes, a plurality of delivery rolls, a plurality of spools each covered with tenacious material and 100 each so carried by a rocker arm as to be in frictional contact with one of the delivery rolls, said rocker arms which are each pivoted to the frame of the machine, a pivot shaft, a plurality of arms fixed thereto each 105 connected with a rocker arm, a trigger arm carried by the pivot shaft, a spring actuated shipper rod, and a collar carried thereby at such a point as to engage the trigger arm.

In testimony whereof I hereto affix my 110 signature in presence of two witnesses.

ABRAHAM G. SHIDEED.
